UNITED STATES PATENT OFFICE.

JOHN P. EUSTIS, OF NEWTON, MASSACHUSETTS.

DESIGN FOR A HOLDER-BRACKET.

42,197.

Specification for Design.

Patented Feb. 27, 1912.

Application filed November 11, 1911. Serial No. 659,831. Term of patent 7 years.

To all whom it may concern:

Be it known that I, JOHN P. EUSTIS, a citizen of the United States, residing at Newton, in the county of Middlesex and State of Massachusetts, have invented a new, original, and ornamental Design for Holder-Brackets, of which the following is a specification, reference being had to the accompanying drawing, forming part thereof.

The figure is a perspective view of a holder bracket showing my new design.

I claim—

The ornamental design for a holder bracket as shown.

In testimony whereof, I have signed my name to this specification in the presence of two subscribing witnesses.

JOHN P. EUSTIS.
